UNITED STATES PATENT OFFICE.

JOHN H. PIFER, OF LARIMORE, NORTH DAKOTA.

SCRAPER MECHANISM.

Application filed March 26, 1923. Serial No. 627,714.

To all whom it may concern:

Be it known that I, JOHN H. PIFER, a citizen of the United States, residing at Larimore, in the county of Grand Forks and State of North Dakota, have invented new and useful Improvements in Scraper Mechanism, of which the following is a specification.

This invention relates to improvements in scraping mechanism for partly or wholly removing snow from the ice on frozen rivers, lakes and the like, and the invention has to do in one embodiment, with that type of scraper wherein the advancing means is in the rear of the scraper. However, my invention has features which are of great utility in horse or other drawn scrapers traversing dry land.

In accordance with my invention, supporting means such as runners or wheels are employed, and a scraper is disposed between said runners in a novel floating or rocking relation with the latter whereby the scraper is adapted for adjustment to scrape the snow or other material irrespective of the elevation of the runners above the ice or other level.

A further feature of novelty consists in means for holding the scraper in different positions to scrape at different levels so that irrespective of the load or resistance, the scraper cannot tilt in either direction from its adjusted position.

A further feature consists in means for sustaining the scraper in a non-scraping loaded position until the scraping mechanism reaches a location where the snow or other material is to be dumped.

A further feature consists in a novel draft connection of the floating scraper with the runners in such relation to the scraping edge of the scraper that the draft pull on the latter will act to depress the scraping edge. A further feature of this draft connection resides in the combination with hoisting means whereby the scraper may readily be shifted into a dumping position without interference with said draft connection.

In the most improved embodiment of my invention, the scraper is rockingly supported on the runners or frame in a manner to readily permit adjustment of the scraper into different positions to limit the depth of action of the scraper edge and also to freely permit the scraper to be shifted by the hoist-

ing means into a dumping position. The return of the scraper to normal, from a dumping position is by gravity, and the novel draft means serves as a guide to hold the scraper in a position whereby it will, when restored, be returned into its normal supported relation.

My invention has many other features of novelty which will be more fully described in connection with the accompanying drawings and which will be more particularly pointed out in and by the appended claims.

In the drawings:

Fig. 1, is a view in side elevation of my complete scraper mechanism, showing the most improved form thereof.

Fig. 2, is a plan view thereof with the traction engine and one rocker rail omitted.

Fig. 3, is a sectional view on line 3—3 of Fig. 2, showing the scraper adjustably held in a position to scrape all the snow off from the ice, the scraping edge riding on the ice level.

Fig. 4, is a similar view showing how the scraper can be adjusted to the same position even when the snow is so deep that the runners are travelling at an elevation with respect to the ice level.

Fig. 5, is a similar view showing the scraper sustained in a non-scraping or loaded position.

Fig. 6, is a similar view showing the scraper shifted by the hoisting means into a snow dumping position.

Fig. 7, is a detail section on line 7—7 of Fig. 2, showing the sliding abutment of the runner frame with the forward portion of the traction engine.

Fig. 8, is an enlarged view of the scraper retaining device and the trip or throw-off means therefor.

Fig. 9, is a sectional view on line 9—9 of Fig. 8.

Fig. 10, is a view in side elevation of the front end of a modified form of mechanism especially designed for dry land work.

Fig. 11, is a plan view of one side portion thereof.

Like characters of reference designate similar parts throughout the different figures of the drawings.

Next describing the specific form shown, 1 designates as a whole, a motive means which is shown in the form of a traction engine of the caterpillar type. As I claim

nothing new in this element, it will be only briefly shown and described. The engine proper is shown at 2, the driver's seat at 3 and the radiator at 4. A hoisting means 5 includes a drum 5, about which a dumping cable 6, is trained, said means being mounted on a frame 7, supported by the tractor. An operating lever 8, for a clutch, (not shown) is accessible from the driver's seat 3, the 10 hoisting means being driven from a chain 9, operated by the engine 2, in any suitable manner. Thus, the driver can throw in the clutch, by shifting lever 8, to actuate the cable 6, or throw out the clutch, at will. 15 On a suitable portion of the tractor, and preferably at the rear sides thereof, are pivot blocks 10, the purpose of which will be later described. Near the front sides of the tractor, are abutments 11, which are 20 shown secured to the tractor at 12, and which retain the runner or supporting frame in parallel relation with the tractor, as will be later described.

I will next describe my improved supporting runner frame structure and the novel manner in which the latter is connected with the tractor.

Said frame includes longitudinal members 13, connected with the tractor by pivots 14 to blocks 10. This pivotal connection near the rear sides of the tractor, forms the rear-most support of the runner frame and permits movement thereof in response to irregular surfaces over which the mechanism 35 travels. The frame members 13, are bent outwardly at 15, a sufficient distance away from the tractor to permit the interposition of abutment means which may take the form of bars 11, previously described. Thus 40 the forward end of the tractor is in sliding abutment engagement with the lateral frame members to retain the latter in parallel relation with the tractor and relieve the pivotal connections 14 of the strain to which they 45 would otherwise be subjected. Said members 13 are connected intermediate their extreme ends by a transverse member 16, and the members 13, are bent outwardly a further distance at 17. Stiffening plates 18, 50 are riveted to said transverse member 16 and to the side members 13, to render the frame rigid. The runner ends of the frame are designated at 19, and the latter are bent outwardly from portions 17, to afford sufficient spread to receive the scraper 20, between said ends 19. The extreme front or runner ends 21, are bent downwardly from the main body of the frame for pivotal connection with runners 22, at 23, which latter 55 are in the form of pivot bolts. The runners 22 are provided on both sides thereof with plates 24, and a bearing bracket 25, on the outside face of each runner, serves as a bearing for the pivot bolt in addition to the bearings afforded by the ends 21 and

runners 22. Thus, I obtain a very strong and efficient pivotal connection between the runners and frame which serves to not only support the front end of the frame, but which securely holds the runners 22 in the 70 desired spaced relation, rearwardly from the front ends of the runners. In practice, I find it advantageous to rigidly connect the front ends of the runners 22 as they avoid running sideways more effectively if the runners are cambered, as clearly shown in Fig. 2. Thus each front end of each runner is provided with a rigidly attached arm 25', extending upwardly therefrom at an angle, as clearly shown in Fig. 3. A rod 26, connects said arms, and surrounding said rod is a spacing sleeve 27 against the ends of which the arms abut. This forms a rigid connecting means which is disposed above any normal level of snow thereby avoiding interference and drag. Further, this connecting means holds the front ends of the runners at the adjusted camber. In practice, I find that with this means of connecting the runners, in addition to the strong 80 pivotal connection of the runners with the frame, I can avoid undue length of the runners and thus eliminate the necessity of any connection of the runners at the rear thereof. Where the runners are relatively short, as shown, turning of the mechanism is greatly facilitated as the runners offer much less resistance than would be the case where the runners are long.

It will now be clear that I provide a rigid 100 supporting or runner frame which is pivoted at its ends, and supported on its pivotal connections with the runners and tractor, and in addition to this distribution of the weight of the frame, I attain maximum 105 flexibility in traversing uneven surfaces. It will be clear that the runners can negotiate a slight incline separately from the tractor, and vice versa, without imposing 110 any binding stresses on the frame. Further, it will be noted from Fig. 1, that the runners and tractor are relatively separated, which is a feature of great advantage in traversing thin ice.

In accordance with my invention, a stationary crane is employed, and in carrying out this feature of wide distribution of weight, I mount this crane on the runner or supporting frame so that not only is the actual weight of the crane divided between 115 the runners and tractor, but also the hoisting thrust, imposed when dumping the scraper.

As shown, crane members 28, are secured at 29, on frame portions 15, and converge at 30, where a pulley or sheave may be rotatively mounted. Supporting members 32, connected with the runner frame and said members 28, rigidly hold the latter in the position shown. The cable 6, is shown 120

trained over pulley 31, and extending downwardly to the scraper, to be presently described.

I will next describe my improved scraper 5 and the manner and means employed for manipulating the same.

The form of scraper is clearly shown in Figs. 2 and 3, the sides being indicated at 33, the rear end at 34 and the scraping edge 10 at 35. The bottom is formed of two sections 36 and 37, in angular relation, the purpose of which will be presently described. One of the novel features of the invention 15 is the floating draft connection of the scraper with the runners, which I will now describe in detail.

To the front inside face of each runner is pivoted at 38, a draft bar 39, which is bent outwardly at 40, to reach inside the 20 scraper, as will clearly be seen in Fig. 2. A pivot bar 41, is permanently pivoted to the scraper at 42, and has an outwardly bent end 43, between which and the side wall of the scraper is interposed the remaining end 25 of bar 39. An adjustable pivot 44, connects said bars 39 and 41, and also extends through the wall of the scraper, a plurality of holes 45, being provided. Thus the draft pull may be set low, intermediate or high, 30 in accordance with the requirements. In any event, this is a floating draft connection as it leaves the scraper free to be adjusted into various scraping positions and also elevated into a dumping position, and in addition to both of these advantages, the draft 35 bars 39 always insure a correct relation of the scraper between the runners, irrespective of the adjustment of the scraper. In other words, the bars 39, not only hold the scraper in its proper lateral position between the runners but also in a proper longitudinal relation thereto.

In accordance with my invention, as shown, the scraper 20 is rockingly supported on a structure in such a novel manner 45 that it can either be bodily elevated into a dumping position or adjusted to scrape at different depths, and finally, it may be sustained in a non-scraping or snow carrying position, as I will now describe in detail.

On the outside face of each side 33, is fixed a rocker or fulcrum rail having a front, rounded fulcrum portion 46, an intermediate normal supporting section 47 and a rearward reclining section 48, at a slight 50 angle to section 47. Section 47, is substantially parallel with bottom section 36 of the scraper and section 48, is substantially parallel with bottom section 37, of the scraper. Thus, in all normal or most frequent adjustments of the scraper 20, the rail section 47, 55 will present a broad bearing engagement with the runner. A most important feature is that the rails engage the tops of the runners so that when the scraper is elevated to dump, the rocking rails are free to leave

the runners, and because of the guiding function of the bars 39, they are bound to engage the runners when the scraper is returned to normal from a dumping position without the necessity of any special guiding 70 means.

These rocking rails may be formed of angle iron, one flange 49, being riveted to the scraper side 33, as shown in Fig. 6.

I will next describe the various positions 75 to which the scraper may be adjusted.

In Fig. 3, I have shown the scraper 20 adjusted with its scraping edge 35, in actual contact with the ice, the level or upper face of which is indicated at A, and the runners 80 22, engaging the ice. This is the adjustment made when all the snow is to be scraped off. However, in some instances, the snow is left on the ice for a thickness of an inch or more, in which event, the scraper will be adjusted 85 with the edge 35 correspondingly above the ice level.

In Fig. 4, I have illustrated an adjustment wherein all the snow is being scraped off and where the depth of the snow is 90 such that the runners are elevated somewhat from the ice level. Thus, the scraper 20 is capable of scraping at a level below the runners.

In Fig. 5, I have illustrated the scraper 95 20 in a non-scraping or material carrying position with the scraping edge 35, elevated considerably above the ice level and the scraper bottom section 37, substantially parallel with the ice. This adjustment shows 100 the section 48 in full engagement with the top of the runners. When a scraper is full, as in this position, and is some distance from the point of deposition where the material is to be dumped, this adjustment is 105 very desirable. The advantage of having sections of the bottom of the scraper in parallel relation with corresponding sections of the rocker rails, will now be clear.

In Fig. 6, I have shown how the cable 6, 110 attached at 50, to the scraper 20 has elevated the latter to a dumping position. Here it will be seen how the draft bars 39, prevent the front end of the scraper 20, from advancing forwardly or shifting rearwardly when the cable 6 elevates the scraper to a dumping position. After the cable is slackened, the scraper 20, will descend into a position that will insure engagement of the rocking rails with the runners. Further, 115 the center of gravity is such that the scraper cannot tip forwardly or to the left of Fig. 6, when the cable slackens but must turn to the right of said figure. It will now be clear that no thrust is imposed on the scraper to dump the same or to restore it to normal.

It may now be stated that when it is desired to dump the scraper 20, the clutch lever 8, is actuated to operate drum 5, and 120 125 130

hoist the scraper to a dumping position, after which the lever 8, is actuated to release the drum 5 from drive engagement, whereupon, the weight of the scraper will 5 itself be sufficient to restore the scraper to normal by gravity.

I will next describe the retaining and sustaining mechanisms for holding the scraper 20 in various positions of adjustment 10 and the means for releasing the scraper from said retaining means.

The back wall 34, of the scraper 20 has a rearwardly projecting flange 51. On the transverse member 16, are abutment means 15 which may consist of two members 52, secured at 53, to said member 16, and extending upwardly at an angle to the vertical and into the path of flange 51. I preferably elongate the free ends of said members as shown at 54, to increase the area thereof, and prevent deformation of the scraper body. When the scraper is full, and adjusted to the non-scraping or carrying position shown in Fig. 5, the center of 20 gravity of the load is such that the scraper will seek such position by gravity. As the flange 51 engages the abutments 52, the latter will sustain the scraper in the position shown. From this position, the hoisting cable can act, without interference, to 25 shift the scraper from the carrying position shown in Fig. 5, to the dumping position shown in Fig. 6.

The retaining means includes a bar 55, pivoted at 56, to a fitting 57, the latter being secured to wall 34. The shape of bar 55, is clear from Figs. 3 to 5. This bar has a series of notches 58, adapted to coact with a keeper 59, mounted in a fitting 60, which 30 is secured to member 16. The free end of said bar is cam shaped, as shown at 61, to ride over said keeper, and a spring 62, secured to wall 34, and bar 55, normally acts to move bar 55 toward, and retain it in engagement with keeper 59. In Fig. 3, the keeper is engaged with the second notch from the top, and in Fig. 4, with the third notch, and it will be readily seen that the range of adjustment is only dependent on 35 the number of notches provided. However, the more important feature resides in the fact that bar 55, when engaged with said keeper, rigidly holds the scraper in its adjusted position, and prevents it from being 40 tilted upwardly and downwardly from such position. When the scraper is in the carrying adjustment shown in Fig. 5, the bar 55, does not function.

I will next describe the means for shifting 45 said bar 55, out of engagement with its keeper.

A fitting 63, mounted on member 16, carries a spindle 64, on which is rigidly secured a throw-off cam 65, which is located abreast 50 of bar 55. Said spindle 64, has an elongat-

ed crank end 66, which is connected at 67, with an operating rod 68. Rod 68 extends through a bearing 69 and has a cranked end 70, in easy access to the foot of the driver. A stop 71, may be provided to limit movement of rod 68, to the right of Figs. 1 and 75 2. A spring 72, secured to crank 66, normally acts to hold the throw-off device in the position shown, with the stop 71, engaging bearing 69.

Assuming that the scraper was held in a fixed position by the retaining device and it was desired to dump the contents, then, the driver would first actuate the rod 68, to disengage the bar 55, from keeper 59, and then, by operating lever 8, to clutch in drum 5, he could quickly dump the scraper. Without leaving his seat, and on return of the scraper, the driver can, by manipulating the lever 8 and rod 68, cause the bar 55, to engage any of the notches with keeper 59.

I will next refer to a modified form of my invention for use as a dirt, manure or other handler.

In equipping the mechanism for traversing a dry land surface, instead of ice, I employ wheels 73, which may be of the castor type, or as shown, of the swivelled type. A fork 74, having a spindle 75, rotatively journaled in a bearing 76, secured to the side frame member 19, forms a support for the front end of the runner or supporting frame. Thus, it will be understood that either the runners 22 or the wheels 73, constitute bearing means for the front end of the supporting frame, each side thereof having a wheel. Hereinafter in the claims, I will refer to the supporting frame and its runners or wheels, as the supporting frame structure. In place of the runners forming a rocking support for the scraper 20, the supporting frame has a ledge 77, secured to each inside face thereof at 78, and rocking rails having portions 46, 47 and 48, identical with the preferred construction, may fulcrum on 100 these ledges in the same manner that they fulcrum on the tops of the runners. In this form, the cable 6, the retaining and sustaining devices, are identical with those shown in the preferred form, in both structure and 105 operation. Likewise, the rear end of the bearing frame is pivoted to the tractor in the same manner as in the first described form.

The side members 19, in this modification, are extended at 79, forwardly of the scraper 20, and a transverse member 80 may be provided to connect the extensions 79. To this transverse member 80, I preferably attach 110 my draft bars 81, the latter being held against lateral movement by collars 82. The remaining ends 83, are pivotally connected at 84, to the scraper 20, in the same manner as in the first described form. Thus, the scraper 20, is in floating draft connection 115 120 125 130

and performs its function in dirt or manure, in the same manner as with snow.

It will now be clear that the frame, in combination with either the wheels or the 5 runners, broadly constitutes a supported structure adapted to be advanced with its front end foremost, and with which forward or foremost end the scraper is associated in the novel manner set forth in the claims.

10 It will be noted that the bottom of the scraper lies very close to the ice or other surface and that no part of the frame structure is between the bottom of the scraper and the ice surface. Therefore, the bottom of the 15 scraper, throughout its length, is entirely unobstructed from engaging the ice or other surface.

The rocking or fulcrum rails on the scraper, in this form, as well as in the preferred form, limit the depth of action of the edge 35, in combination with the retaining means, for any scraping function. When the scraper is not functioning as a scraper but as a carrier, then, the rocking rails coact 25 with the sustaining members 52.

It will now be clear that the retaining means operates in perfect co-ordination with the floating draft connection of the scraper, and also with the rocking rails, irrespective 30 of the adjustment desired.

It will also be seen that should the scraper become stuck, the tractor may be reversed and the mechanism backed out of a stalled position, the draft bars 39 acting as struts 35 to force the scraper 20 to partake of this retraction.

It is believed that the device of my invention will be fully understood from the foregoing description and while I have shown 40 specific forms of my invention, I do not wish to be limited thereto except for such limitations as the claims may import.

I claim:-

1. A snow scraper mechanism comprising, 45 a traction engine, a runner frame connected with said engine and extending forwardly thereof, runners connected with the front of said frame to be pushed by said engine, and a scraper in floating connection with said runners, and the bottom of said scraper lying close to and being unobstructed from engagement with the ice or other surface.

2. A snow scraper mechanism comprising, 50 a traction engine, a runner frame connected with said engine and extending in front thereof, runners on the front of said frame, a scraper in draft connection with said runners, and means on said scraper for rockingly engaging said runners.

60 3. A snow scraper mechanism comprising a traction engine, a runner frame connected with said engine and extending in front thereof, runners at the front of said frame, a scraper in floating connection with said 65 runners and the bottom of said scraper be-

ing free to engage the ice or other surface, and means for retaining said scraper in position to scrape at different levels with respect to the ice level.

4. A snow scraper mechanism comprising, 70 a traction engine, a runner frame connected with said engine and extending forwardly thereof, runners connected with the front of said frame, a scraper in draft connection with said runners, a notched bar pivoted to 75 said scraper, a member on said frame for selective engagement with the notches in said bar to hold said scraper in different depth scraping positions.

5. A snow scraper mechanism comprising, 80 a traction engine, a runner frame and runners adapted to be pushed by said engine, a scraper in draft connection with said runners, a notched bar pivoted to said scraper at the rear thereof, a member on said frame 85 for selective engagement by the notches in said bar to hold said scraper in different depth scraping positions, and a trip device for throwing said bar out of engagement with said member to release said scraper. 90

6. A snow scraper mechanism comprising a traction engine, a runner frame structure connected with said engine, a scraper in draft floating connection with said structure, a notched bar pivoted to said scraper, 95 a member on said structure for selective engagement with the notches in said bar to hold said scraper in different positions, a spring for retaining said bar in engagement with said member, a trip device for throwing said bar out of engagement with said member, and a spring for normally holding said trip device free from said bar. 100

7. A snow scraper mechanism comprising, 105 a traction engine having a hoisting drum, a runner frame pivoted to said engine and extending forwardly thereof, runners supporting the forward end of said frame, a scraper in floating draft connection with said runners, said scraper having rocking 110 rails engaging said runners to support said scraper in different positions of adjustment, and a cable connected with said scraper and operated by said drum to manipulate said scraper. 115

8. A snow scraper mechanism including 120 runners, and a scraper between said runners and having rocking rails engaging said runners to support said scraper in different positions of adjustment.

9. A snow scraper mechanism including 125 runners, a scraper between said runners having fixed rocking rails engaging said runners to support said scraper in different positions, and draft means connected to the forward portions of said scraper and to the forward ends of said runners.

10. A snow scraper mechanism including 130 runners, a scraper between said runners having rocking rails engaging the tops of said

runners, each rail having a rounded front fulcrum section, an intermediate normal supporting section and a rearward reclining section disposed at an angle to said normal section.

11. A snow scraper mechanism including a propelled frame, runners in supporting engagement with said frame and adapted to run on snow at different levels above the 10 ice level, a scraper between said runners, and means for holding said scraper in positions to scrape snow at different depths below the level at which the runners are travelling.

15. 12. A scraper mechanism comprising, a supported frame structure adapted to be advanced with its front end foremost, and a scraper in floating draft connection with and also in floating rocking coaction with 20 the front end of said structure.

13. A scraper mechanism comprising, a supported frame structure adapted to be advanced with its front end foremost, and a scraper in floating connection with the front 25 end of said structure, and the bottom of said scraper lying close to and being unobstructed by said structure from engaging the ice at the front and rear end of said scraper.

30. 14. A scraper mechanism comprising, a supported structure adapted to be advanced with its front end foremost, a scraper near the front of said structure and the bottom of said scraper being unobstructed from and 35 adapted to lie close to the ice or other surface, means for bodily elevating said scraper independently of said structure and into a substantially vertical dumping position, and means pivotally connecting said scraper 40 with said structure.

45. 15. A scraper mechanism comprising, a supported structure adapted to be advanced, a scraper having rocking rails coacting with said structure to support said scraper in a load carrying position, a floating draft connection uniting said scraper with said structure and normally acting to dispose said scraper into a load carrying position, and an abutment means preventing 50 said scraper from tilting beyond a load carrying position.

50. 16. A scraper mechanism comprising, a

supported frame adapted to be advanced, a scraper having rocking rails coacting with said structure to support said scraper in a 55 load carrying position, and a floating draft connection uniting said scraper with said structure and acting to tilt said scraper into a load carrying position.

17. A scraper mechanism comprising, a 60 supported structure adapted to be advanced, a scraper in floating draft connection with said structure and having free rocking coaction therewith, whereby said floating scraper may ascend and descend relatively 65 to said structure, and retaining means for holding said scraper against tilting from various operative positions irrespective of ascent or descent of said floating scraper.

18. A scraper mechanism comprising, a 70 frame having forwardly extending ends, short runners pivoted to said ends rearwardly of the front ends of said runners, a scraper between and connected with said runners and having a rear end extending 75 rearwardly of the rear ends of said runners and a forward end disposed rearwardly of the front ends of said runners, and means rigidly connecting the front ends of said runners above the snow level, whereby short 80 runners may be employed with a large capacity scraper.

19. A scraper mechanism comprising, a supported frame structure adapted to be advanced and having front ends in lateral 85 spaced relation, a scraper between said front ends and the bottom of said scraper being unobstructed from and in close relation to the ice surface, and means for advancing said scraper with said structure. 90

20. A scraper mechanism comprising, a supported frame structure adapted to be advanced and having front ends in lateral spaced relation, a scraper between said front ends and being unobstructed by said structure 95 from engaging the ice surface, means for holding either the front or rear ends of said scraper substantially in engagement with the ice surface, and means connecting said scraper with said structure. 100

In testimony that I claim the foregoing as my own, I hereby affix my signature.

JOHN H. PIFER.
